UNITED STATES PATENT OFFICE.

EVERETT V. ANDERSEN, OF TYLER, MINNESOTA.

DEVICE FOR CURING INGROWN TOENAILS.

Application filed February 18, 1928. Serial No. 255,380.

The present invention relates to an appliance for remedying and curing ingrown toe-nails, which, for various reasons, grow into the flesh of the toes at the corners of the nails, causing irritation, swelling and pain, especially when the shoe presses the nail down against the flesh.

An object of the invention is to provide an extremely simple device for ready application to the ingrown toe-nail and operable for effectively lifting the corners thereof away from the flesh, so as to afford prompt relief from pain and irritation, to correct the position and form of the nail, and to give the flesh an opportunity to heal.

A further object is to so construct the device that it may be readily adjusted to toenails of slightly different widths.

A still further and important object is to provide manually adjustable means for positively lifting the corners of the nail in a most efficient manner.

The invention consists in the novel form, combination and arrangement of parts hereinafter more fully described, shown in the accompanying drawing and claimed.

In the drawing:

Figure 1 is a plan view of the device applied to a toe-nail.

Figure 2 is a front elevational view thereof; and

Figure 3 is an enlarged perspective view of the device, detached.

Referring more in detail to the drawing, the present device or appliance consists of a comparatively stiff and flat cross bar 5 adapted to be placed on and to extend transversely of the toe-nail 6, adjusting screws 7 carried by and depending from the ends of the cross bar, and toe-nail edge or corner lifters embodying nut members 8 adjustably threaded on the depending stems of the adjusting screws and having depending and inwardly facing hooks 9 adapted to be engaged under the side edges of the nail. The screws 7 extend through and are free to be turned in openings 10 provided in the ends of the cross bar, the heads of the screws engaging the upper surface of the latter.

Although it is intended to provide cross bars of different lengths to suit the requirements of toe-nails of materially different widths, slight adjustments may be made by elongating the holes 10 longitudinally of the cross bar as shown, thereby permitting limited lateral adjustment of the screws and edge

lifters towards or away from each other. It is obvious, however, that the holes 10 may be round and only large enough to receive the screws. A pair of spaced hooks 9 is preferably formed integral with each nut member to engage the nail at spaced points, as shown, whereby tearing of the toe-nail is rendered unlikely and proper lifting of the edges of the nail insured.

To prevent lateral slipping of the cross bar, the under surface of the latter is preferably roughened, as at 11, intermediate its ends where it engages the nail.

In use, the cross bar is laid across the nail and the hooks of the edge lifters are engaged under the side edges of the nail. The screws are then turned so that they are threaded into the nut members 8 of the lifters, causing the latter to be positively elevated until the edges of the nail have been lifted to the required extent. In this way, the corners of the nail are positively lifted away from the flesh so as to give prompt relief from irritation and pain.

Minor changes may be made without departing from the spirit and scope of the invention as claimed.

What I claim as new is:

1. A device for remedying ingrown toe-nails comprising a stiff substantially flat cross bar adapted to be placed on and to extend across the nail, and toe-nail edge lifters suspended from the ends of and vertically adjustable relative to said cross bar.

2. A device for remedying ingrown toe-nails comprising a cross bar, adjusting screws carried by and depending from the ends of the cross bar, and toe-nail edge lifters embodying nut members adjustably threaded on said adjusting screws below the cross bar.

3. A device for remedying ingrown toe-nails comprising a cross bar, adjusting screws carried by and depending from the ends of the cross bar, and toe-nail edge lifters embodying nut members adjustably threaded on said adjusting screws below the cross bar, said cross bar having end openings in which the adjusting screws are mounted for freely turning.

4. A device for remedying ingrown toe-nails comprising a cross bar, adjusting screws carried by and depending from the ends of the cross bar, and toe-nail edge lifters embodying nut members adjustably threaded on said adjusting screws below the cross bar, said cross bar having end openings in which the

adjusting screws are mounted for freely turning, said openings being elongated to permit lateral adjustment of the adjusting screws toward or away from each other.

5. A device for remedying ingrown toe-nails comprising a cross bar, adjusting screws carried by and depending from the ends of

the cross bar, and toe-nail edge lifters embodying nut members adjustably threaded on said adjusting screws below the cross bar, said cross bar having its lower surface roughened where it engages the nail. 10

In testimony whereof I affix my signature.

EVERETT V. ANDERSEN.
